UNITED STATES PATENT OFFICE

HANS TREDE AND OTTO H. HARTMANN, OF KASSEL-WILHELMSHOHE, GERMANY,
ASSIGNEES TO SCHMIDT'SCHE HEISSDAMPF-GESELLSCHAFT MIT BESCHRANKTER
HAFTUNG, OF KASSEL-WILHELMSHOHE, GERMANY, A CORPORATION OF GERMANY

INDIRECT GENERATION OF STEAM BY MEANS OF SUPERHEATED HEATING STEAM

Application filed February 7, 1929, Serial No. 338,156, and in Germany February 15, 1928.

Our invention relates to the indirect generation of steam by transferring heat from superheated steam to heating elements immersed in the water in the evaporator drum or 5 like container of the boiler.

In such methods as hereinbefore proposed, it is necessary that the heating steam on admission to a heating element should be in such a condition as regards pressure and temperature that during its passage through the 10 heating element, the heat required for evaporating the water in the boiler drum should be given up in the form of superheat and latent heat; and in certain cases, moreover, part 15 of the necessary heat is taken from the sensible heat of the condensed heat carrier.

By reason of such requirements, definite limits are imposed on the range of utility of known methods.

20 As a rule, the pressure of the heating steam must be higher than that of the steam generated, because only in such conditions is it possible to impart the necessary heat content to the heating steam.

25 Our present invention affords a method by which steam can be generated indirectly by the use of the superheated steam without the necessity of satisfying the condition or requirement above set forth.

30 On the contrary, it is possible to apply as the heat carrier heating steam of any desired pressure, and in particular steam of a low-pressure, and at the same time to generate working steam of any required pressure even 35 up to the critical point.

With this object, successive transfers of heat to the water to be evaporated are effected by leading superheated heating steam alternately through superheater elements heated 40 from the outside and through heating elements lying in the evaporator drum.

The present invention consists in the use as heat carrier of working steam which is led through heating stages on its way from the 45 generator to the engine, heat exchanger or the like, where it is used, the pressure of generation being higher than the working pressure at the place where it is used by such an amount that the difference of pressure secures the flow of heating steam through the 50 heating stages.

With the new method of working, no special auxiliary apparatus, such as circulating pumps, is necessary in order to drive the heating 55 steam through the heating elements, nor

is such a considerable degree of cooling required that the difference of weight of the heating steam in the inlet pipe and the condensate in the outlet pipe is relied on to ensure flow through the heating elements.

The number of heating stages is determined according to the conditions of the particular case concerned.

For example, if high-pressure steam of 50 atmospheres is to be generated and steam of 65 17 atmospheres superheated to 475° C. is used as heating steam and is taken in the form of saturated steam from an existing boiler plant, the number of heating stages is determined as follows:

The heat content of the heating steam of 70 17 atmospheres pressure and with a superheat of 475° C. amounts according to the usual steam table (Mollier entropy diagram) to 815 kcal/kg. In respect of this heat content, a fall of temperature is available to the 75 temperature of the saturated steam to be generated at 50 atmospheres, that is to a temperature of about 263° C., the assumption being made that the heating steam is cooled to this temperature. According to the steam 80 table, the heat content of the heating steam at this temperature amounts to 703 kcal/kg. The heat available, therefore, amounts to 815 - 703 = 112 kcal/kg.

If, for example, it is further assumed that the high-pressure steam boiler is fed from the heating-steam boiler with feed water at 200° C., then according to the steam table, the heat required for evaporation amounts to 90 664.5 - 200 = 464.5 kcal/kg.

The necessary number of heating stages thus amounts to

$$\frac{464.5}{112}$$

that is 4.15 stages or in practice 5, or to give a certain reserve, 6 heating stages would be 100 provided.

If it is desired, with the same heating steam, to generate high-pressure steam of 224 atmospheres, that is, of the critical pressure, heat must be supplied to the amount of 105 508 - 200 = 308 kcal/kg. The temperature of saturated steam at 224 atmospheres is about 874° C., and the heat content of the heating steam of 17 atmospheres at this temperature is about 763 kcal/kg. so that the available 110

heat is $815 - 763 = 52$ kcal/kg. The number of heating stages is therefore

$$\frac{308}{52}$$

that is 5.92 stages.

In this way, for any desired pressure up to the critical pressure of the working steam to be generated, the number of heating stages 10 can be calculated.

If it is desired, with a definite quantity of heating steam, to generate not the same quantity of working steam, but x -times the quantity, then x -times the number of heating 15 stages shown by the above calculations must be used.

With the present invention, the pressure of the heating steam can be chosen within wide limits and in particular steam of very low 20 pressure can be efficiently used as heating steam.

For example, if working steam of 50 atmospheres is to be generated by means of heating steam of 1.4 atmospheres superheated to 475° C., and the temperature of the feed water is 105° C., then for the evaporation of a kilogram of water at 105° C. in the working boiler, $664.5 - 105$, i. e., 559.5 kcals 25 are necessary. From the steam table the heat content of the heating steam superheated to 475° C., is 818 kcal/kg. and at the temperature of the saturated steam to be generated at 50 atmospheres, that is 263° C., it is 715 kcal/kg., so that the heat available is 30 $818 - 715 = 103$ kcal/kg.

It will be seen, therefore, that in this case the number of stages amounts to

$$\frac{559.5}{103} = 5.43 \text{ stages.}$$

The necessary heating steam can be taken from any suitable steam generator, for example, as mentioned above, from an existing low-pressure boiler.

The present invention, however, is not confined to the application of heating steam whose pressure is lower than that of the steam to be generated. It is, for example, possible to utilize indirectly-generated high-pressure steam as heating steam and to lead it from the evaporator directly without loss of pressure to the first heating stage. Further, if desired, the pressure of the heating steam taken from the indirectly-heated evaporator may be reduced before admission to the heating stages.

When heating up a boiler according to the present invention, it is important to provide for the generation of heating steam in the heating-steam superheater itself from distilled water introduced into the first superheater stage, such water evaporating in the first superheater stages and being superheated in the following stages.

In order, therefore, to accelerate the gen-

eration of steam in the superheater, the pressure in the heating system is reduced by leading the heating steam from the last heating stage into the atmosphere or into a condenser.

For the generation of high-pressure steam of a given temperature in accordance with the present invention, the choice of heating steam is not confined to a comparatively narrow zone of pressures but can be made within wide limits, so that the present invention is specially suitable for increasing the power of existing steam-power plants by the addition of a new high-pressure stage. The initial pressure of the heating steam can then be chosen to correspond with the steam pressure supplied by the existing boiler installation and the superheating elements for the heating stages of the high-pressure steam generator can be built into the existing boiler.

The admission steam pressure of the existing engine installation is reduced in comparison with the pressure before alteration of the plant, so that in this way the pressure drop necessary for causing the heating steam to flow through the heating stages is obtained and the outlet steam coming from the heating stages may be admitted to a low-pressure stage of the engine.

In all cases, due to the fact that the flow of heating steam through the heating stages is ensured solely by a pressure drop between the heating-steam inlet and outlet, the advantage is gained that the high-pressure evaporator may be arranged in any desired position, as, for example, at a level below that of the heating-steam generator.

In the accompanying drawings, different constructional forms of the invention by way of example are shown diagrammatically for carrying out the present method of working:

Figure 1 shows a vertical section of an indirectly-heated steam generator applied to a marine cylindrical boiler of usual construction;

Figure 2 being a cross section on the line II-II of Figure 1;

Figure 3 shows a longitudinal section of a modified form of a marine steam boiler installation;

Figure 4 shows a cross section of a stationary boiler plant; while

Figure 5 shows a longitudinal section of a locomotive and

Figure 6 a diagram of a modified form of construction of a two-pressure boiler installation.

In the form of the invention shown in Figures 1 and 2, the cylindrical boiler, 1, serves for the generation of the low-pressure steam while high-pressure steam is generated in the drum, 2, by the indirect method of heating.

The hot gases from the furnaces, 3, pass through the reversing chamber, 4, and the

smoke tubes, 5, which for the sake of clearness are not shown in Figure 1, to the uptake, 6.

The heating stages through which the heating steam flows comprise alternating superheater elements and heating elements.

In the example illustrated, six heating stages are provided of which each consists of a superheater element, 8, lying in the reversing chamber and a heating element, 9, lying in the water space of the boiler drum, 2. Between the steam space of the cylindrical boiler and the first superheater element is connected a heating-steam pipe, 10, while from the heating element, 9, of the last heating stage, an outlet steam pipe, 11, is led to the outside of the steam drum. The connecting pipes, 12, between a superheater element, 8, and the corresponding heating element, 9, as well as the connecting pipes, 13, between a heating element, 9, and the next following superheater element, 8, are each led respectively through one of the smoke tubes, 5.

The heating steam from the boiler, 1, flows therefore through the inlet pipe, 10, into the first superheater element, 8, then to the first heating element, 9, in the boiler drum and thence alternately through a superheater element and an evaporator element till it passes from the last evaporator element, 9, through the exhaust pipe, 11, to the place where it is used.

To the steam inlet pipe, 10, a feed pipe, 14, is connected through which in case of need distilled water can be introduced into the first superheater stage, 8, so that in this way heating steam can be generated in the first heating stage itself. The necessity may arise, for example, in heating up the boiler before the low-pressure boiler has started to make steam. In order to accelerate the generation of steam in the heating stages, the heating system is connected by a pipe, 15, branching off from the outlet pipe, 11, to a condenser. By a feed pipe, 18, provided with a pump, 19, feed water from the low-pressure boiler, 1, can be passed to the steam-and-water drum, 2.

The high-pressure steam generated in the evaporator drum is led through a pipe, 20, into a superheater arranged in the reversing chamber of the cylindrical boiler, 1, from which the superheated high-pressure steam flows through a pipe, 22, to the cylinder, 23, and thence to the cylinder, 24, of a compound high-pressure engine.

The steam from the low-pressure cylinder, 24, exhausts into the heating-steam outlet pipe, 11, coming from the heating stages so that the high-pressure exhaust steam is mixed with the heating steam. As the temperature of the high-pressure steam generated indirectly in the drum, 2, is substantially higher than the saturated-steam temperature of the heating steam, the heating steam

flowing in the pipe, 11, from the heating stages is still superheated and in consequence the mixture formed from the high-pressure exhaust steam and the heating steam is suitable for doing work in a low-pressure steam engine.

In the form of the invention shown in the drawings, it is assumed that the steam mixture does work in the cylinders, 26 and 27, of the machine installation originally present, the new high-pressure cylinders, 23, 24, being added to the existing cylinders, 26, 27. The admission pressure of the steam to the cylinders, 26 and 27, is reduced as compared with the corresponding pressure before rebuilding so that compared to the admission pressure of the heating steam to the first heating stage, which corresponds approximately to the original boiler pressure, a sufficient pressure drop is provided to ensure an efficient velocity of flow through the heating stages.

In the form of the invention shown in Figure 3, the heating steam is also generated in a cylindrical boiler, 28, with smoke tubes, 29, the flow of hot gases corresponding to that of a ship's boiler with return flue. The furnace is not, however, arranged in the flue but in a combustion chamber lying below the boiler, 28, this combustion chamber, 30, being shut off with respect to the boiler, 28, by a cover, 31.

The products of combustion from the furnace are drawn rearwards into a vertical flue, 32, which is formed by a cross wall, 34, introduced into the reversing chamber, 33, the gases after passing through the flue, 32, flowing through the reversing chamber, 33, into the smoke tubes, 29, and thence to the uptake, 35.

The indirectly-heated steam-and-water drum, 2, lies above the front part of the combustion chamber and is protected from the direct action of the heat of the furnace by a cover, 36.

Each of the successive heating stages, of which for the sake of clearness only four are shown, consists as before of a superheater element and a heating element. The superheater elements, 38, are arranged as walls round the combustion chamber and receive radiant heat from the furnace. The heating elements, 39, can extend along the drum in a longitudinal direction in order to provide the necessary heating surface.

To the first heating element, 38, is connected the heating-steam inlet pipe, 40, through which is led the heating steam generated in the boiler, 28. To the heating-steam inlet pipe, 40, is connected a feed pipe, 41, through which on heating up the installation distilled water may be fed into the heating element of the first heating stage so that heating steam may be generated in the superheater. The heating-steam flows alternately through a superheater element, 38, and a heating ele-

ment, 39, and is finally led from the last heating element through the heating-steam outlet pipe, 42, to the place where it is used. From the outlet pipe, 42, branches off a pipe, 43, by means of which the heating stages during heating up can be connected to a condenser. The high-pressure steam generated indirectly in the drum, 2, flows through a pipe, 44, to a superheater, 45, arranged in the flue, 32, and thence through a pipe, 46, to wherever it is required.

While in the form of the invention described, the heating steam is generated in a low-pressure boiler, in the stationary boiler shown in Figure 4, the heating steam is taken from the indirectly-heated high-pressure drum, 2, in a manner already known in connection with other methods of steam generation. The drum, 2, lies above the furnace which is provided with nozzles so that it may be fired either with oil or pulverized coal. The combustion chamber, 48, forms a vertical flue which at its upper end is connected by a horizontal flue, 49, with a second vertical flue, 50, into which the hot gases are drawn in the direction from above downwards to the chimney. The heating elements, 51, lying in the steam drum, 2, as before, alternate with superheater elements heated from the outside.

Three of the superheater elements shown, namely, the superheater elements, 52, are arranged on the walls of the combustion chamber and receive radiant heat from the furnace. In the fourth superheater element are interposed the tubes, 53, forming in known manner a cooling grate for the slag while the superheater element, 54, to the last heating stage is arranged in the horizontal flue, 49. From the last heating element, 51, the heating steam is led first through a superheater, 55, lying in the flue, 50, and thence through a pipe, 56, to the place where it is used.

In order to be able to generate heating steam in the superheater elements of the heating stages during heating up, a steam pipe, 59, is connected to the heating-steam inlet pipe, 58, leading to the first superheater element, 52, while a pipe, 60, leading to a condenser is connected to the heating-steam outlet pipe, 56.

The high-pressure steam generated in the drum, 2, flows through a pipe, 61, to a superheater, 62, lying in the flue, 50, and thence through a pipe, 63, to the place where it is used.

Below the superheater, 62, in the flue, 50, a feed-water heater, 64, is arranged from which the preheated feed-water is led through a pipe, 65, to the steam drum, 2.

The superheater elements of the heating stages in this form of invention are, as will be seen from the above explanation, built and arranged in a different manner and are

disposed essentially so that the superheating elements through which the heating steam of higher pressure passes lie where the highest combustion-chamber temperatures rule, while the following superheater elements corresponding to the fall in pressure of the heating steam as it passes through the heating stages are arranged at points of lower temperature. This arrangement gives the advantage that the heating steam which has the greatest density flows through the superheater elements subjected to the highest temperature so that the latter are efficiently cooled and protected from burning.

It is obvious that the area of the heating surfaces of the successive heating stages must be designed to suit the above-mentioned conditions.

In the diagrammatic drawings this point, which is valid for all forms of the invention shown, has not been taken into consideration.

In the locomotive shown in Figure 5 the heating steam is again generated in a low-pressure boiler, in the present case of the longitudinal type, below which the steam drum, 2, is arranged.

The superheater elements, 69, of the heating stages which alternate with the heating elements, 70, lying in the drum, 2, extend to the fire-box through a large-diameter tube, 71, provided in place of the usual smoke tubes. The heating steam is led from the steam drum, 73, through a pipe, 74, to the heating element, 69, of the first heating stage and from the heating element of the last heating stage through a pipe, 75, to the low-pressure cylinder, 76, of the locomotive.

To the heating-steam inlet pipe, 74, as before, a feed-pipe, 78, is connected and to the heating-steam outlet pipe, 75, a branch pipe, 79, through which the heating steam during heating up can pass into the atmosphere.

The high-pressure steam generated in the drum, 2, is led through a pipe 80, to a superheater, 81, lying in the tube, 71, and the fire-box, 72, and thence through a pipe, 82, to the high-pressure cylinder, 83.

The exhaust steam from the high-pressure cylinder flows through a pipe, 84, to the heating-steam outlet pipe, 75, to mix therein with the heating steam before admission to the low-pressure cylinder, 76.

In contrast to the form of the invention shown in Figure 4, in which from the indirectly-heated steam drum only a part of the high-pressure steam is taken to serve as heating steam for the heating stages, while the other or larger part of the heating steam is led after superheating directly to the engine, in the form of the invention shown in Figure 6, the whole of the high-pressure steam generated indirectly in the boiler drum, 2, flows through the heating stages before passing thence to the engine.

The heating stages each consists of a super-

heater element, 85, arranged as radiant heat-receiving surfaces in the furnace and heated from outside and a heating element, 86, lying in the boiler drum, 2. To the first superheater element, 85, is led the whole of the high-pressure steam from the drum, 2, through a pipe, 88. This steam then flows alternately through a superheater element, 85, and a heating element, 86, and passes from the last heating element, 86, to the heating-stage outlet steam pipe, 89.

To the first superheater stage, 85, is connected a feed pipe, 90, and to the outlet pipe, 89, is connected a branch pipe, 91, through which, when heating up, the outlet-steam pipe can be connected to atmosphere or to a condenser. The exhaust steam pipe, 89, is connected by way of a control valve, 92, with a superheater, 95, lying in the smoke tubes, 93, of a smoke-tube boiler, 94, from which superheater a pipe, 96, leads to the high-pressure stage of the engine.

In addition, a branch pipe, 99, provided with a control valve, 98, is led from the outlet-steam pipe, 89, into the water space of the smoke-tube boiler, 94. If the valve, 98, is closed, all the high-pressure heating steam passes through the superheater, 95, and the pipe, 96, to the high-pressure stage of the engine after it has served in the heating stages by alternate superheating and giving up heat to generate high-pressure steam indirectly in the drum, 2.

The admission pressure in this stage of the engine is so much less than the working pressure in the drum, 2, that the necessary velocity of flow is ensured through the heating stages.

Since, in the heating elements, 86, and especially in the last heating stages, the heating-steam pressure is less than the working pressure in the drum, 2, the heating steam in the heating elements cannot cool down to a temperature corresponding to the temperature of saturated steam at this lower heating steam pressure, and consequently cannot condense when flowing through the heating elements.

On the other hand, the result of opening the valve, 98, is that a part of the heating steam coming from the heating stages flows into the water space of the low-pressure boiler, 94. This fraction of the heating steam flowing into the low-pressure boiler, 94, can be regulated by appropriate adjustment of the two valves, 92 and 98.

In the case when all the heating steam is admitted into the low-pressure boiler, the necessary pressure drop is likewise obtained in order to secure an efficient flow of the heating steam through the heating stages.

The steam generated in the low-pressure boiler, 94, flows through a pipe, 100, to a superheater, 101, arranged in the smoke-tubes,

93, of the boiler, 94, and thence through a pipe, 102, to the low-pressure stage of the engine.

What we claim is:

1. Steam generating plant comprising in combination an indirectly heated steam boiler, a source of heating steam, and heating stages each consisting of a superheater element heated from the outside and a heating element lying in the boiler drum, successively passed by the heating steam, the superheater elements of the heating stages traversed by the heating steam of highest pressure being arranged to be exposed to the highest temperatures.

2. The method of continuously generating steam from a body of water already heated above its evaporation temperature, which comprises conducting steam generated from said water and then alternately superheating it and passing it in heat exchange relationship with said water without mixing it therewith a plurality of times, and finally utilizing it at a pressure lower than its initial pressure thereby to induce a flow thereof.

3. Steam generating plant comprising a boiler drum, a plurality of heating elements in the drum, a plurality of superheaters, said heating elements and superheaters being alternately connected in series, and a conduit connecting the steam space of said drum with said series connected superheaters and heating elements.

4. In a multi-stage boiler installation generating working steam at a plurality of pressures in a plurality of sections for discharge to a plurality of working points, a plurality of heating elements in one of the sections, a plurality of superheaters in the path of the furnace gases, said heating elements and superheaters being alternately connected in series, and a conduit connecting the steam space of one of the boiler sections with said series connected superheaters and heating elements to supply steam to said elements at a pressure not greater than that of the steam in the section containing the heating elements.

5. The method of continuously generating steam from a body of water, which comprises successively passing heating steam in heat exchange relation with a flow of hot gases to superheat the same and then passing the thus superheated heating steam in heat exchange relation with said water a plurality of times, and finally utilizing the heating steam for the performance of mechanical work at a pressure lower than its initial pressure, the heating steam being at least a portion of the steam generated from said body of water.

In testimony whereof we affix our signatures.

HANS TREDE.
OTTO H. HARTMANN.
